Des. 181,079
Patented Sept. 24, 1957

181,079

ELECTRIC STORAGE BATTERY

Charles A. Toce, Sunland, and Robert Broussard,
Glendale, Calif.

Application December 17, 1953, Serial No. 28,121

Term of patent 7 years

(Cl. D26—5)

The single figure of the drawing is a perspective view of an electric storage battery showing our new design. The opposite side and end, not shown, have substantially the same appearance as the side and end shown in the figure. Portions of the figure of the drawing are lined diagonally to indicate transparency.

We claim:

The ornamental design for an electric storage battery, as shown and described.
